UNITED STATES PATENT OFFICE.

JOSEPH WILLETS, OF TRENTON, NEW JERSEY.

DESIGN FOR A VEGETABLE-DISH.

SPECIFICATION forming part of Design No. 15,362, dated August 26, 1884.

Application filed February 29, 1884. Term of patent 3½ years.

To all whom it may concern:

Be it known that I, JOSEPH WILLETS, of Trenton, in the county of Mercer and State of New Jersey, have invented and produced a 5 new and original Design for a Vegetable-Dish, of which the following is a full, clear, and exact description.

Reference is to be had to the annexed drawing, forming a part of this specification, in 10 to which a side view of the newly designed vegetable-dish is shown, the cover being raised.

In my newly-designed vegetable-dish the bottom edge of the dish A is provided at each corner with a leg, B, and between the legs 15 with a downwardly-curved ornament, C. The handles D on the ends of the dish consist of an upwardly and outwardly inclined part, E, from the outer end of which a slightly-curved part, F, extends down to a point on the end 20 of the dish below the part E, so that the entire handle will be inclined upward and outward. The handle is flat—that is, the two parts of which it is composed are above each other and in the same vertical plane. The 25 cover G is provided with an offset, H, a short

distance from the bottom edge, and about one-third of the width of the cover from the said edge it is provided with a second offset, H', between which offsets a slightly-convex part, J, is formed on the cover, which offsets and 30 curved part J extend entirely around the cover. The handle K of the cover consists of a segmental part, having a serrated upper edge and circular heads at the ends, at which ends the handle is secured on the cover. 35

I claim—

The herein-described newly-designed vegetable-dish, consisting of a dish provided with corner legs B and ornaments C between the legs, the sides of the dish being curved upward and outward to near the top, then curved inward, and terminating in a beveled part, which dish is provided with handles having upwardly-curved parts F, and the parts E, 40 which extend down to the ends of the dish, 45 substantially as herein shown and described.

JOSEPH WILLETS.
